CLAIM

The ornamental design for a baby bottle nipple, as shown and described.

DESCRIPTION

FIG. 1 is a top, front, right perspective view of a first embodiment of a baby bottle nipple;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a cross-sectional elevation view of the baby bottle nipple, taken in the direction of line 8-8 of FIG. 6;

FIG. 9 is a top, front, right perspective view of a second embodiment of a baby bottle nipple;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof;

FIG. 15 is a bottom plan view thereof;

FIG. 16 is a cross-sectional elevation view of the baby bottle nipple, taken in the direction of line 16-16 of FIG. 14;

FIG. 17 is a top, front, right perspective view of a third embodiment of a baby bottle nipple;

FIG. 18 is a front elevation view thereof;

FIG. 19 is a rear elevation view thereof;

FIG. 20 is a right side elevation view thereof;

FIG. 21 is a left side elevation view thereof;

FIG. 22 is a top plan view thereof;

FIG. 23 is a bottom elevation view thereof; and,

FIG. 24 is a cross-section elevation view of the baby bottle nipple, taken in the direction of line 24-24 of FIG. 22.

The equal-length broken lines depict portions of the baby bottle nipple that form no part of the claimed design.
